UNITED STATES PATENT OFFICE.

JACOB F. PRATT AND WELLINGTON CHASE, OF COLDWATER, MICHIGAN.

SLEIGH.

SPECIFICATION forming part of Letters Patent No. 364,295, dated June 7, 1887.

Application filed October 1, 1886. Serial No. 215,072. (No model.)

To all whom it may concern:

Be it known that we, JACOB F. PRATT and WELLINGTON CHASE, citizens of the United States, residing at Coldwater, in the county of Branch and State of Michigan, have invented 5 certain new and useful Improvements in Sleighs; and we do hereby declare the following to be a full, clear, and exact description of the invention, such as will enable others skilled 10 in the art to which it appertains to make and use the same.

Our invention relates to improvements in sleighs; and it consists in the construction and arrangement of the parts of the same, which 15 will be more fully hereinafter described and pointed out in the claim.

Heretofore sleigh-bodies have been formed with sides, back, bottom, and dash-board constructed separately and individually, and afterward joined by suitable and well-known means, and it has not been an unfrequent occurrence that said parts have become disjointed by warping and wear, and especially 25 is this true of the bottom and dash-board which forms the essential feature of our invention.

The object of our invention therefore is to provide a combined bottom and dash-board constructed of a single piece of suitable material, the dash-board portion of which is suitably bent and rolled to obtain the desired curvature, presenting thereby a pleasing configuration to the eye, and whereby a strong, durable, and inseparable bottom and dash-board is cheaply manufactured. We attain 30 these objects by the construction shown in the accompanying drawings, wherein like letters of reference indicate similar parts in the several views, and in which—

Figure 1 is a perspective view of a sleigh 40 embodying our improved combined bottom and dash-board. Fig. 2 is a detail perspective view of our improvement.

A indicates the bottom portion, and B the dash-board, the said dash-board being suitably 45 curved to attain the desired result and present a pleasing configuration to the eye. At the point b, where the two parts are formed into each other, an easy and graceful curve is formed, devoid of irregularity and weakness, which is 50 obtained by dispensing with the use of saw-cuts to aid in the formation of the dash-board.

Near the bend formed between the dash-board and the bottom, and adjacent to the dash-

board, projecting shoulders b' b' are formed, which are adapted to engage with the side 55 pieces of the sleigh when the parts are joined. By the formation of these projections the dash-board is made somewhat larger than the bottom portion of the sleigh, thereby providing means for a close joining of the parts, so that 60 they will present a neat and strong appearance. Suitable holes, a a, are formed in the bottom portion A, which receive the securing-bolts uniting the several parts.

The combined bottom and dash-board is 65 formed of a straight piece of well-seasoned wood, the shoulders b' b' being formed before the dash-board is bent into shape. By the use of steam or by any other well-known means, the dash-board is then bent by being passed 70 through suitable machinery well known in the art. After the proper curvature has been obtained, the combined bottom and dash-board is then allowed to dry, retaining its curvature, when it can be suitably polished or painted 75 and be readily joined to the other parts. This construction of combined dash-board and bottom is especially applicable to children's sleighs, which are generally weak at these 80 points.

By this construction strength and durability are combined in a simple, efficient, and comparatively inexpensive manner, thus providing means whereby the construction of a sleigh-body entire is more readily and quickly 85 accomplished.

Having thus described our invention, what we claim as new, and desire to secure by Letters Patent, is—

As an article of manufacture, a combined 90 sleigh - bottom and dash - board formed of a single piece of wood, the dash-board portion of which is bent into shape to attain the desired curvature, and shoulders, such as b' b', formed at the lower portion of the dash-board 95 for facilitating an easy and efficient joining to the other parts of the sleigh, substantially as described.

In testimony whereof we affix our signatures in presence of two witnesses.

JACOB F. PRATT.
WELLINGTON CHASE.

Witnesses:
